UNITED STATES PATENT OFFICE

RODOLFO E. ELIZONDO, OF MONTERREY, MEXICO

LAMP

Application filed June 26, 1929. Serial No. 373,728.

This invention relates to new and useful improvements in lamps.

The invention has for an object the provision of a device of the class mentioned which is of simple durable construction, dependable in use and efficient in action, and which may be manufactured and sold at a reasonable cost.

The invention proposes a lamp wire frame 10 supporting a block provided with battery cells inserted thru the bottom and held by springs, and closed by a bottom cap, a lamp supported on the block, a hinge reflector with a lamp on the wire frame, and wiring 15 for connecting the lamp and battery, controlled by a switch upon the handle, and means may be provided for simultaneously disengaging the springs holding the cells.

For further comprehension of the invention, and of the objects and advantages thereof, reference will be had to the following description and accompanying drawings, and to the appended claims in which the various novel features of the invention 25 are more particularly set forth.

In the accompanying drawing forming a material part of this disclosure:—

Fig. 1 is a side elevational view of a device constructed according to this invention, a portion thereof being broken away for disclosing interior parts.

Fig. 2 is a horizontal sectional view taken on the line 2—2 of Fig. 1.

Fig. 3 is a view similar to Fig. 2 but illustrating a modified form.

Fig. 4 is a fragmentary sectional view taken on the line 4—4 of Fig. 3.

The reference numeral 10 indicates generally a horizontal base wire ring, 11 a horizontal intermediate wire ring and 12 a horizontal top wire ring. A plurality of spaced vertical wire ribs 13 are connected with these rings for forming a lamp wire frame. Each of the wire ribs is of curved form and spread 40 at the bottom and bent inwards between the bottom ring and the intermediate ring as indicated by reference numeral 14. The bottom end of each of the vertical ribs is rolled around the bottom ring as shown at 15. The 45 top end of each of the ribs is rolled as at 16

around the top ring 12. A plurality of clips 17 connect the intermediate horizontal ring 11 with the vertical ribs.

A handle 18 extends materially above the top horizontal ring 12 and is connected at its bottom on diametrically opposite ribs 13. A circular block 18 is secured within the lamp frame particularly upon the inwardly bent portions 14 of the vertical ribs 13 between the bottom and intermediate horizontal rings. The vertical ribs are urged into engagement with the block 18 by a wire 19 curled around the frame. Preferably the block 18 is secured to the vertical ribs by solder.

The block 18 is formed with a reduced top portion 20 having a shoulder 21, and an electric bulb 22 is mounted in the top of the block. A lamp glass 23 rests upon the shoulder 21 and encircles the lamp 22. A plurality of cylindrical openings 24 are formed within the block 18 and communicate with the bottom thereof. These openings have top shoulders 25. Battery cells 26 are engaged within the openings 24 and rest against the shoulders 25. Retaining springs 27 engage against the bottom of the battery cells for holding them in place, and screws 28 serve to attach the springs to the bottom of the block 18. A bottom cap 29 threadedly engages upon the bottom of the block 18 and serves to cover the battery cells from view.

A top cover 30 constituting a reflector is provided with arms 31 hingedly connecting with the top horizontal ring 12. This top reflector may also be provided with a lamp 32. Schematic wiring 33 is shown forming a circuit connecting the battery cells with the lamps 22 and 32. This circuit includes a switch 34 mounted upon the handle 18. The schematic wiring shown illustrates only the one live lead, and the ground being depended upon for completing the circuit.

In the modified form of the device illustrated in Figs. 3 and 4, a ring 35 has been shown mounted upon the bottom of the block 18. This ring is provided with pegs 36 engaging in slots 37 formed in the block for limiting moving of the ring, said moving being rotative. Several handles 38 project 95 100

from the ring 35 providing for its manual turning. Arms 39 project from the ring 35 and are provided with end pins 40 engaging in slots 41 formed in the springs 27. The springs 27' are swivelingly held by the screws 28. In normal positions, these springs 27' hold the battery cells against displacement. The ring 35 may be manually turned with the aid of the handles 38 so that the pins 40 moving in the slots 41 cause the spring 27' to simultaneously disengage from the battery cells. Dot and dash lines 42 indicate the disengaged positions of the springs.

The lamp may be carried by the handle 18 and the lights 22 and 32 lit by operating the switch 34. When the battery cells become inoperative, they may be replaced by first disengaging the bottom cap 29 and then moving the springs for permitting their removal. New cells may be engaged in place of the old ones and the lamp is again ready for use.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A lamp of the class described, comprising a wire frame, a block supported therein, a lamp mounted on the block, a lamp glass encircling the lamp, battery cells mounted in the block and electrically connected with the lamp, springs swivelingly mounted for holding the battery cells in place and formed with slots, and means for simultaneously moving said springs into inoperative positions including pins engaging in said slots and supported on a ring adjustable in said block.

2. A lamp of the class described, comprising a wire frame, a block supported therein, a lamp mounted on the block, a lamp glass encircling the lamp, battery cells mounted in the block and electrically connected with the lamp, springs swivelingly mounted and holding the battery cells in place, and means for simultaneously moving the springs into inoperative positions.

3. A lamp of the class described, comprising a wire frame, a block supported therein, a lamp mounted on the block, a lamp glass encircling the lamp, battery cells mounted in the block and electrically connected with the lamp, springs swivelingly mounted and holding the battery cells in place, and means for simultaneously moving the springs into inoperative positions, said means including a ring adjustable on the said block.

In testimony whereof I have affixed my signature.

RODOLFO E. ELIZONDO.
